MITER GAUGE

William H. Woodward, Detroit, Mich.

Substituted for abandoned application Serial No. 162,167, September 2, 1937. This application September 5, 1941, Serial No. 409,707.

9 Claims. (Cl. 143—169)

This invention relates to miter gauges, such as are employed to position a piece of work in a required definite angular relation to a cutting tool, as for example, a circular saw. This is a substitute for my application Serial Number 162,167, filed September 2, 1937, and abandoned.

In the use of such gauges, certain angles, such as ninety and forty-five degrees, are much more commonly required than others, and it is desirable to afford a particularly quick and accurate setting of the instrument for such angles, eliminating such errors as are likely to arise from dependence on the registration of gauge markings. It is common practice to mount a work-engaging member for pivotal adjustment on a supporting member, and to provide markings on said members registrable to establish selective definite angular relations between the members.

An object of the invention is to provide a third member, movable about the axis of pivotal adjustment independently of the two aforesaid members, and limited in its movement by the supporting member to adapt it to serve as a stop for the work-engaging member, in certain definite angular positions of the latter.

Another object is to employ a common means for pivotally connecting the work-engaging member and said third member to the supporting member.

A further object is to so interpose the third member between the supporting and work-engaging members that all three members may be clamped in fixed relation by a common means.

A further object is to mount on the third member various elements adjustable to assure accuracy of the angular relations established through use of such member.

These and various other objects are attained by the construction hereinafter described and illustrated in the accompanying drawing, wherein:

Fig. 1 is a top plan view of the improved gauge, as adjusted to establish a ninety degree relation between the work-engaging straight edge and the supporting bar of the gauge.

Fig. 2 is a bottom plan view of the gauge, showing a forty-five degree adjustment thereof.

Fig. 3 is a front view of the gauge, corresponding to Fig. 1.

Fig. 4 is a vertical sectional view, taken on the line 4—4 of Fig. 1, radially to the axis of angular adjustment.

Fig. 5 is a top plan view of a small gauge plate marked with a line to which graduations of the instrument may be selectively set.

In these views, the reference character 1 designates an elongated supporting bar surmounted at one end by a block 2, welded or otherwise rigidly attached to the bar. Rigidly set into the bar 1, some distance from said block, is a post 3, and pivoted thereon is a plate 4 of approximately semicircular shape, its front edge 5 forming an arc exceeding ninety degrees, centered at said post and extending in close proximity to the block 2. The latter is preferably concaved in conformance to such arc. The rear edge of the plate 4 is vertically flanged to form a work-engaging fence 6, preferably slightly to the rear of the pivot post. Extending rearwardly from the arcuate edge 5, is a set of graduations serving, in conjunction with an index line 7 on the block 2, to indicate in degrees the angular relation of the fence 6 to a saw or some other tool (not shown) operative on work (not shown) positioned against the fence. For reasons herein-after explained, it is preferred to form said index line on a small sheet metal element 8, clamped on the block 2 by a screw 9, and so slotted to receive such screw (see Fig. 5) as to afford a slight adjustment of said element laterally of the block. To permit of securing the plate 4 to the bar 1, in any adjusted position of said plate, a clamping nut 10 is threaded on the upper portion of a post 11, rigidly set into said bar, and freely extending upwardly through a slot 12, forming an arc centered at the post 3. Said nut is adapted to apply clamping pressure to the plate through a washer 13 bridged across the slot 12, as best appears in Fig. 4.

Describing now a provision for accurately setting the gauge, without depending on the described graduations, 14 designates a member of sector shape, mounted at its approximate apex on the post 3 between the bar 1 and plate 4, and pivotal independently of said bar and plate, the arcuate front edge 14a of such member being preferably flush, or approximately so, with the front edge of said plate. An aperture 15 in said member freely accommodates the post 11, and allows the member to undergo an angular travel approximating forty-five degrees without interference by the post 11. The member 14 either entirely or to a large extent transmits the weight of the plate 4 to the bar 1, thus adapting the clamping nut 10 to secure both said plate and member to the bar, in any adjusted positions. At the extremities of its arcuate forward edge, the member 14 has a pair of forward projections at opposite sides of the block 2, one integrally carrying a lug 16 projecting toward the block,

and the other mounting a stop screw 17 having an end portion projecting toward the block 2. Said forward projections of the member 14 further integrally carry a pair of upstanding stops 18, which mount a pair of stop screws 19, each having an end portion projecting away from the block 2. At the ends of its arcuate edge 5, the plate 4 is increased in radius to form a pair of shoulders 20 for abutting the screws 19, as will be presently explained. Each of the screws 17 and 19 carries a lock nut 21, and is adapted to be held thereby in a selected longitudinal adjustment.

In the use of the described gauge, adjustment of the plate 4 for any angle other than forty-five or ninety degrees, is effected by registering a selected graduation on said plate with the index line 7. To establish either forty-five degree position, the plate 4 is swung toward the desired position, thus engaging one of the shoulders 20 with the corresponding stop-screw 19. Thereupon the member 14 swings in unison with said plate, until the movement of both is terminated by engagement of either the lug 16 or stop screw 17 with the block 2. If said screw is properly set, either of the two forty-five degree positions, whereof one is illustrated in Fig. 2, will be accurately established by the described adjustment.

To establish the ninety degree position of the plate, either shoulder 20 is brought into engagement with the corresponding screw 19, while the lug 16 or screw 17 remote from said corresponding screw is engaging the block 2, as is exemplified in Fig. 1. The desired position being thus established, the nut 10 is tightened to maintain such position.

In initially setting the instrument, the member 14 is first swung to engage the lug 16 with the block 2 and is retained in such engagement while the screw 19 remote from such lug is adjusted until the plate 4, in engaging such screw, establishes an exact ninety degree relation between the fence and the cutting path of the saw or other tool (not shown), to which the gauge is accessory. Next, the plate 4 and member 14 are swung clockwise in unison until the screw 17 encounters the block 2. Said screw is now adjusted until the fence 6 occupies an exact forty-five degree relation to the cutting path of the tool. While the member 14 is held in the position just described, the plate 4 is now swung until the screw 19 adjacent to the lug 16 is engaged by the corresponding shoulder 20. Said screw is now adjusted until an exact ninety degree relation exists between the fence 6 and the path of the cutting tool. Finally, the element 8 is laterally adjusted until the index line 7 registers accurately with the proper graduation of the plate 4, when the latter is in any of its positions determined by the member 14, and is firmly secured in such adjustment by the screw 9.

When thus set, the gauge will permit establishment of forty-five or ninety degree adjustments much more rapidly and with greater assurance of accuracy than is possible when the settings are effected by registration of markings.

It is often the practice to alternatively dispose the bar 1 in either of two grooves (not shown) formed in a saw table at opposite sides of a saw, and such grooves do not always occupy the exactly parallel relation that is essential to accurate functioning of miter gauges as heretofore constructed. The present gauge, however, permits of compensation for any such error since there are two ninety degree quick settings and

these can be so differentiated as to be respectively suited for use according as the bar 1 is disposed in the respective grooves.

The term "stop" as used in the appended claims, applies to the lug 16, also to the adjusting screw 17, and further to each adapting screw 19.

The invention is presented as including all such modifications and changes as come within the scope of the following claims.

What is claimed is:

1. A miter gauge comprising a supporting member, a supported member having a work-engaging face, a pivotal connection between such members, a third member mounted on one of the first-mentioned members and movable with respect to the first-mentioned members about the axis of said connection, an index element on one of the two first-mentioned members, the other first-mentioned member having a set of graduations extending in an arc centered at said axis, and selectively registrable with the index element, and a pair of stops on the third member, one positioned for engagement with the supporting member, to determine a certain position of engagement of the other stop by the supported member, such position establishing a predetermined angular relation between said work-engaging face and the supported member.

2. A miter gauge comprising a supporting member, a supported member having a work-engaging face, a third member interposed between the first-mentioned members, a common means for pivoting the supported member and third member on the supporting member, affording them relative angular travel about their common pivotal axis, and a pair of stops on the third member, one coating with the supporting member and the other with the supported member, to establish the work-engaging face in a desired definite angular relation to the supporting member.

3. A miter gauge comprising a supporting member, a supported member having a work-engaging face, a pivotal connection between such members, a third member mounted on one of the first-mentioned members and movable with respect to both first-mentioned members about the axis of said connection, an index element on one of the two first-mentioned members, the other first-mentioned member having a set of graduations extending in an arc centered at said axis and selectively registrable with the index element, an abutment carried by the supporting member, a pair of stops carried by the third member, at opposite sides of the abutment, and engageable with the abutment to establish different limiting angular positions of the third member, a second pair of stops carried by the third member, at opposite sides of the abutment, for engagement by the supported member, each stop of the second pair having two positions of use established by engagement with the abutment of the first-mentioned pair of stops, whereby said abutment and stops are adapted to establish four different angular positions of the supported member.

4. A miter gauge comprising a supporting member, a supported member having a work-engaging face, a third member interposed between the two first-mentioned members, a pivot member mounting the supported member and third member coaxially on the supporting member, and affording them individual angular travel, the third member having limiting engagement with the supporting member in two different angular posi-

tions thereof, and the supported member having two stops angularly spaced as regards rotation about the pivot member and alternatively engageable with the third member in each of its said angular positions, whereby each of said positions of the third member determines two different definite positions of the supported member.

5. A miter gauge comprising a supporting member, a supported member having a work-engaging face and an arcuate edge and a set of graduations extending from said edge, a pivotal connection between said members at the axis of said arcuate edge, a third member mounted on one of the first-mentioned members and movable with respect to the first-mentioned members about said axis, and having an arcuate edge approximately flush with that of the supported member, an index element on the supporting member correlated with said graduations, and a pair of stops on the third member, one positioned for engagement with the supporting member, to determine a certain position of engagement of the other stop by the supported member, such position establishing a predetermined angular relation between said work-engaging face and the supported member.

6. A miter gauge comprising a supporting member, a supported member, a pivotal connection between such members, a third member mounted on one of the first-mentioned members and movable about the axis of said connection, the supported member having opposed edges, one forming a work-engaging face and the other forming an arc centered at the axis of said pivotal connection, an index element on the supporting member, a set of graduations being extended on the supported member from its arcuate edge for selective registration with the index element, an abutment rigidly carried by the supporting member in proximity to said arcuate edge, and a pair of stops carried by the third member adjacent to said arcuate edge and at opposite sides of the abutment, one of such stops being engageable with said abutment in a predetermined

position of the third member, and the supported member having a part engageable with the other stop in said position of the third member, whereby a predetermined angular relation of said work-engaging face to the supporting member may be established in said position.

7. A miter gauge as set forth in claim 6, the supported member having two shoulders, respectively engageable with the respective stops, to establish desired angular positions of the work-engaging face, in two positions of the third member, in which positions, the other stop engages said abutment.

8. A miter gauge as set forth in claim 6, the supported member having two shoulders, respectively engageable with the respective stops, to establish desired angular positions of the work-engaging face, in two positions of the third member, in which positions, the other stop engages said abutment, each of said stops comprising an adjusting screw to engage the coacting shoulder of the supported member and one of said stops comprising an adjusting screw for engaging said abutment.

25 9. A miter gauge comprising a supporting member,
a supported member having a work-engag-
ing face, a third member interposed between the
two first-mentioned members, a pivot member
mounting the supported member and third mem-
30 ber coaxially on the supporting member, and
affording them individual angular travel, a pair
of stops on the third member alternatively en-
gageable with the supporting member to estab-
lish either of two limiting positions for said
35 travel of the third member, the supported mem-
ber having two stops angularly spaced as regards
rotation about the pivot member and alterna-
tively engageable with the third member in each
of said limiting positions of the third member,
40 whereby each of said positions of the third mem-
ber determines two different definite angular po-
sitions of the supported member.

WILLIAM H. WOODWARD.
